DESIGN FOR A COMBINED LAMP AND DESK SET

Gustav J. Sengbusch, Milwaukee, Wis.

Application October 5, 1936, Serial No. 65,167

Term of patent 7 years

To all whom it may concern:

Be it known that I, Gustav J. Sengbusch, a citizen of the United States, residing in Milwaukee, county of Milwaukee, and State of Wisconsin, have invented a new, original, and ornamental Design for a Combined Lamp and Desk Set, of which the following is a specification, reference being had to the accompanying drawing, forming a part thereof.

Fig. 1 is a side elevation of a combined lamp and desk set embodying my new design;

Fig. 2 is an end elevation, and

Fig. 3 is a plan section on the line 3—3 of Fig. 1.

I claim:

The ornamental design for a combined lamp and desk set substantially as shown.

GUSTAV J. SENGBUSCH.
